UNITED STATES PATENT OFFICE

104,586

DESIGN FOR A LADY'S HEAD COVERING

Samuel Sheindelman, New York, N. Y.

Application July 11, 1936, Serial No. 63,776

Term of patent 3½ years

To all whom it may concern:

Be it known, that I, Samuel Sheindelman, a citizen of the United States, residing in Lawrence, Nassau County, Long Island, New York, have invented a new, original, and ornamental Design for a Lady's Head Covering, of which the following is a specification, reference being had to the accompanying drawing, forming a part thereof, in which:

Fig. 1 is a side elevation of a lady's head covering showing my new design;

Fig. 2 is a front elevation thereof.

I claim:

The ornamental design for a lady's head covering as shown.

SAMUEL SHEINDELMAN.
